(57) **CLAIM**

The ornamental design for a display screen panel with graphical user interface, as shown and described.

DESCRIPTION

FIG. 1 is a first embodiment of a display screen panel with graphical user interface, illustrated in a first state.

FIG. 2 illustrates the display screen panel with graphical user interface of FIG. 1 in a second state.

FIG. 3 is a second embodiment of a display screen panel with graphical user interface, illustrated in a first state; and, FIG. 4 illustrates the display screen panel with graphical user interface of FIG. 3 in a second state.

The appearance of the animated graphical user interface sequentially transitions between FIG. 1 and FIG. 2 in the first embodiment, and between FIG. 3 and FIG. 4 in the second embodiment. The process or period in which one image transitions to another forms no part of the claimed design. The outer perimeter illustrated by dashed broken lines in the drawings illustrates a display screen panel and forms no part of the claimed design. The remaining broken lines illustrated portions of the graphical user interface that form no part of the claimed design.

1 Claim, 4 Drawing Sheets
